FIG. 5.

H. R. Walker INVENTOR
BY *Howard H. Winslow* ATTORNEY.

Patented June 10, 1924.

UNITED STATES PATENT OFFICE.

WILLARD ROBERT WALKER, OF SYRACUSE, NEW YORK, ASSIGNOR TO WALKER
BROTHERS COMPANY, OF SYRACUSE, NEW YORK, A CORPORATION OF NEW YORK.

KITCHEN FIXTURE.

Application filed April 21, 1919. Serial No. 291,683.

To all whom it may concern:

Be it known that I, WILLARD R. WALKER, a citizen of the United States of America, and resident of Syracuse, in the county of 5 Onondaga, in the State of New York, have invented new and useful Improvements in Kitchen Fixtures, of which the following, taken in connection with the accompanying drawings, is a full, clear, and exact description.

This invention relates to certain improvements in kitchen fixtures or culinary utensils combining in a single apparatus a sink and a dish washing machine as a unitary 15 article of manufacture, the object of which is to obtain the conveniences of both within a relatively small compact space, and thereby avoid the inconveniences attending the use of a dish washing machine and a 20 sink separate from each other, it being understood that one of the strongest arguments against the use of separate dish washers is that they occupy considerable room and necessarily have to be moved 25 from place to place along the floor in order to permit freedom of movement of the help around the room in which it is usually located.

Another object is to connect the hopper 30 of the sink or dish washer to a single drain pipe through the medium of separate valved conduits so that water or other fluid may be retained in either receptacle or discharged therefrom independently of the 35 other.

Other objects and uses relating to specific parts of my invention will be brought out in the following description:

In the drawings,

40 Figure 1 is a perspective view of the combined sink and dish washer vat, the draining connections and fluid agitating device being omitted.

45 Figures 2, 3 and 4 are sectional views taken respectively on lines 2—2, 3—3 and 4—4, Figure 1, omitting the vat or tank and drainage connections, the vat being shown in part by dotted lines in Figure 2.

Figure 5 is a front elevation of the complete apparatus connected for use. 50

Figure 6 is an enlarged detail sectional view through one side of the vat-supporting shelf and adjacent portion of the vat showing the manner of connecting those parts, 55 taken on line 6—6 Figure 5.

Figure 7 is an enlarged detail sectional view taken on line 7—7 Figure 5.

Figure 8 is a horizontal sectional view taken in the plane of line 8—8 Figure 7.

As illustrated, this fixture comprises a 60 substantially rectangular one-piece frame or bracket —1— of cast metal or other suitable material, the main body of which is disposed in a substantially horizontal position, and is provided near one end with a 65 depressed portion —2— to form a liquid container or sink, the remaining portion of the main body constituting a laterally extending shelf of the sink and being formed with a circular opening —3— and adapted 70 to receive and support the upper end of an upright vat —4— of a dish washing machine of the class set forth in my Patents #1,265,010 May 7th, 1918, and #1,244,446 75 Oct. 23, 1917, except that the motive power for driving the agitator is preferably supported by the vat, the outlet of which together with that of the sink —2— being 80 connected by branch conduits —5— and —6— to a common drainage pipe —7—, the branches —5— and —6— being provided with valves —8— similar to that shown in 85 my Patent No. 1,304,519, of May 20, 1919, for controlling the discharge of liquid from the vat and sink respectively but independently of each other.

A raised rib or flange —9— extends around the entire marginal edge of the frame integral therewith, the portions at the rear of the depression —2— and opening —3— being extended upwardly some distance above the remaining portions to form the upright back plates —10— and —11—, the plate —10— at the rear of the depression —2— being of considerably 95 greater height than the plate —11—, both

plates serving to protect the wall to which the frame is secured against disfigurement by the spattering of liquid used in the sink or vat.

- 5 The front and end edges of the frame —1— are also provided with pendant marginal flanges —12— for reinforcing purposes which enables the frame to be made of comparatively thin cast metal. The depressed portion —2— extends downwardly some distance below the lower edge of the flange —12— and is substantially rectangular in top plan but of greater length from front to rear than from side to side, 10 the bottom of the depression being provided with a central circular opening —13— for receiving a drainage hopper —14— to which the upper end of the drainage pipe —6— is connected.
- 15 20 The upper end of the opening —13— is enlarged to form an inclined ledge —15— which is engaged by an annular flange —16— forming an integral part of the hopper —14— and serving to support said hopper against downward displacement. The intermediate portion of the hopper is threaded externally and engaged by a suitable nut —17— carrying a packing —18— which is tightly secured against the under 25 side of the adjacent portion of the bottom of the depression —2— to rigidly clamp the hopper in place.
- 30 35 This hopper is formed with an integral grid —19— substantially midway between its lower and upper ends for preventing the passage of solid matter into the drain pipe —6—, but as a further precaution against the entrance of such solid matter to the grid, I have provided a sheet metal screen —20— 40 preferably of spring metal and having its central portion concavo-convex in cross-section with its concave side uppermost, the upper marginal edge of said screen being detachably interlocked with an inner annular 45 rib —21— of the adjacent portion of the hopper —14—, said screen being held in operative position by its own tension and may be removed when necessary for cleansing purposes.
- 50 55 The portion of the frame —1— which surrounds the opening —3— constitutes an annular flange —22— extending downwardly from the upper surface of the main body of the frame at one side of the depressed portion —2—, and having its lower end offset inwardly to form an annular ledge —23—, the lower side of which is provided with an annular groove —24— in which the upper edge of the vat —4— is seated and held in 60 fixed relation to the frame —1— by suitable cement, solder or equivalent fastening means —25—.

65 The vat —4— is adapted to contain the necessary quantity of washing fluid together with a suitable agitator therefor, and a dish

supporting tray substantially as shown in my patents above referred to, and not necessary to herein illustrate or describe other than to state that the shaft for driving the agitator extends through the apex of the 70 conical bottom of the vat coaxial with the opening 3 and is preferably driven by an electric motor —A— carried by and below the vat and geared to the shaft in any well known manner.

75 By closing the valve —8— in the branch pipe —6— enables the washing fluid or other liquid to be retained in the sink or depressed portion —2— for washing purposes, if desired, or the valve may be opened at will to 80 discharge the liquid from the sink without disturbing the valve in the branch pipe —5—.

85 In similar manner the valve —8— in the branch pipe —5— may be opened or closed at will independently of the valve in the branch —6— to retain or discharge the washing fluid in or from the vat —4—.

90 In some instances, the main drain pipe —7— may be provided with a valve —7'— which may be closed at will, under which conditions the valves —8— in the branches —6— and —5— may be opened to allow water or other liquid to pass from the sink —2— into the lower portion of the receptacle —4— which extends downwardly some distance below the bottom of the sink as shown more clearly in Figure 5, it being understood that only a small quantity of water or washing fluid is needed in the bottom of the vat —4— of the dish washer just sufficient to cover the agitator, the latter being usually arranged in the conical bottom of the container.

95 100 For example, hot or cold water may be supplied to the sink through one or more faucets —a—, and if it is desired to use soapy water in the initial cleansing of the dishes in the vat —4—, it may be properly mixed in the sink —2—, and then allowed to discharge 105 into the lower portion of the vat —4— through the branches —6— and —5— by simply closing the valve —7'— and opening both valves —8—.

110 After the initial cleansing of the dishes with soapy water through the medium of the agitator (not shown) in the vat —4—, the contaminated water may be drawn off at will by simply opening the valve —7'— after 115 which the last named valve may be again closed and fresh water supplied from the sink through the branches 6 and 5 to the vat —4—, and the cleansing operation continued by the operation of the agitator.

120 125 The primary object of the screen —20— is to concentrate and collect any solids which may result from the cleansing of utensils, and to permit said screen with the solids therein to be removed and discharged into a waste receptacle (not shown) thereby

obviating the use of the objectionable sink screens now in common use. washer having the upper end of its vat seated in said channel. ¹⁰

What I claim is:

A kitchen fixture comprising a sink having a laterally extending shelf provided with a circular opening therethrough, and having an annular channel in its under side around the opening, and a mechanical dish

In witness whereof I have hereunto set my hand this 18th day of April, 1919.

WILLARD ROBERT WALKER.
